(57) **CLAIM**

We claim the ornamental design for a contoured seating assembly, as shown and described.

DESCRIPTION

FIG. 1 is a top perspective view of a contoured seating assembly of the present invention, where a top rear perspective view is identical thereto;

FIG. 2 is a top plan view thereof;

FIG. 3 is a rear elevation view thereof;

FIG. 4 is a left side elevation view thereof;

FIG. 5 is a front elevation view thereof; and,

FIG. 6 is a right side elevation view thereof.

The broken lines depict portions of the contoured seating assembly that form no part of the claimed design.
